TAMPER-RESISTING PROTECTIVE DEVICE

Elmer H. Taylor, Newburyport, Mass., assignor
to The Chase-Shawmut Company, Newbury-
port, Mass., a corporation of Massachusetts

Application September 18, 1946, Serial No. 697,662

8 Claims. (Cl. 200—119)

1

This invention relates to improvements in thermal protective cut-outs for electric circuits. More particularly it relates to such cut-outs of the fuse plug type wherein the fuse plug is mounted in a cut-out base receptacle which may be equipped with means for coaction with the plug to make it difficult to restore a circuit through the assembly, following an interruption by the fuse plug, excepting by substitution of a new fuse plug having a rated current-carrying capacity not greater than what has been predetermined as proper for any particular installation.

The prevalent and dangerous practices of fuse-tampering and over-fusing are the direct and contributing causes of numerous fires each year, which take human lives and destroy and damage inestimable amounts of property. The sole purpose of a fuse in an electric circuit is to ensure against the continuance of a dangerous circuit abnormality for a period long enough to destroy wiring insulation or to cause damage to apparatus which may be connected in the circuit. When a fuse of predetermined proper rating is in a circuit, it stands as a sentinel ever ready to interrupt the circuit in response to any circuit abnormality whose continuance beyond a predetermined period of time would create a fire hazard or be otherwise dangerous and objectionable. But, when, through ignorance or design, a circuit is over-fused by insertion in the base receptacle of a fuse having a current-carrying rating substantially above what has been predetermined as the maximum safe operating current for any particular circuit, the substituted fuse cannot protect the circuit because the fuse is adapted to carry currents substantially above what has been predetermined as the maximum safe current for the particular circuit.

Similarly, following blowing of a fuse, if the interrupted circuit is completed through the cut-out assembly by make-shift means inserted in the assembly to bridge or otherwise by-pass the blown fusible element of the fuse plug, that protection which it is the sole purpose of the fuse in the circuit to provide is lost if, as is usual, the make-shift means has current-carrying capacity appreciably greater than that of the fuse plug prior to the blowing thereof.

The serious nature of the problems of over-fusing and fuse-tampering are recognized and emphasized in the National Electrical Code, shortly to become effective, which includes mandatory provisions making it requisite, in all new fuse plug installations, to employ only so-called

2

type S fuse plugs which have been approved or tentatively approved by the Electrical Committee as adapted, when mounted in a cut-out base receptacle, to make it acceptably difficult both to over-fuse a circuit and to bridge or otherwise by-pass the fusible element of a blown fuse in a cut-out assembly.

Numerous fuse plugs and fuse plug assemblies as proposed heretofore embody means for coacting in a cut-out assembly to make it difficult either to over-fuse a circuit or to bridge or otherwise by-pass the fusible element of a blown fuse plug, by make-shift means inserted in the cut-out assembly. However, it has been recognized that any satisfactory or generally acceptable program to minimize the hazards and the dire effects of fuse-tampering and over-fusing must take into consideration the some two hundred million standard Edison base fuse plug receptacles embodied in present installations. The mentioned mandatory provisions of the National Electrical Code apply only to new installations, yet it has been generally recognized by those responsible for the Code provisions and by fuse manufacturers and large users of fuses, such as public utility organizations, that any fuse plug acceptable as satisfying the requirements of the Code for new installations should be adaptable also for operative embodiment in any of the presently installed standard Edison base cut-out receptacles.

The so-called type S fuse plug which presently is designated by the Code, under its said mandatory provisions, includes an adapter which is a necessary part of the fuse assembly and which makes it possible to mount the type S fuse plug in any standard base receptacle. But the type S plug, with its adapter, costs more than the conventional fuse, and public utility organizations, whose responsibility it is to replace blown fuses in a large percentage of the standard base receptacles now in use, realize that many of their customers may prefer the lower cost conventional fuse replacement. Hence, an objection of the public utility organizations to the type S fuse plug is that both conventional and type S fuses, the latter with their adapters, would have to be carried in stock. Also there has been general criticism of the type S fuse plug because certain peculiarities of its structure involve special manufacturing procedures which would tend to restrict manufacture of special parts of the plug and adapter.

While it is quite universally agreed that it is highly desirable and essential that it be made

mandatory in new installations to employ fuse plugs which effectively resist fuse-tampering and over-fusing, very strong opposition has been raised to designation, under the mandatory requirements, of a fuse plug structure which cannot be open to general competition in its manufacture and which requires a relatively expensive adapter to permit operative mounting of it in a standard Edison base receptacle. Even the International Association of Electrical Inspectors, which has been a primary force back of the movement to obtain acceptance, under the Code, of the type S fuse plug and adapter structure, has felt called upon to advocate an intensive educational program which it affirmatively states must be put into effect if the type S fuse is to be successful.

Another objection to the so-called type S fuse plug and adapter assembly is that the fuse plug, when mounted in a base receptacle, projects from the receptacle substantially beyond the plane of maximum projection of the conventional fuse plug. Actually the type S fuse projects approximately one-quarter of an inch further out from a base receptacle than does the conventional plug. Inasmuch as many of the present installations have the base receptacles and fuses enclosed within containers whose covers, when closed, just slightly clear the outer ends of the conventional fuse plugs, the substitution of type S fuse plugs and adapters makes it impossible to close the covers of the containers.

It is among the objects of the invention to provide a fuse plug which may be mounted in the standard Edison-base receptacle either with or without means for coaction with the fuse plug to make the assembly acceptably resistant to fuse-tampering and over-fusing. I provide a fuse plug having a standard screw-shell contact for screwing directly into the screw-shell contact of the standard cut-out base receptacle, and having a standard center contact for directly engaging the center contact of the base receptacle, so that the fuse plug requires no adapter for the operative mounting of it in the standard cut-out base receptacle and which projects from the base receptacle no more than the conventional fuse plug. However, the body portion of the fuse plug, which carries its center contact, has reduced diameter for nicely fitting within a tamper-resisting sleeve member which may precede the fuse plug into the base receptacle and which has an annular portion for extending between the screw-shell contact and the reduced portion of the fuse plug for isolating from each other the center and screw-shell contacts of the receptacle, and for coaction with the fuse plug in making the assembly acceptably resistant to fuse-tampering and over-fusing.

Another object is to provide a fuse plug having an insulating body which may be economically molded or otherwise formed in one or more parts according to conventional procedures, and which may have an exteriorly smooth body portion for coaction with tamper-resisting means 65 interiorly of a fuse plug receptacle to effectively resist fuse-tampering and over-fusing.

Still another object is to provide a fuse plug assembly comprising a fuse plug, a standard cut-out base receptacle and a tamper-resisting insulating sleeve insert, wherein both the fuse plug and the sleeve are exteriorly threaded for screwing directly into the screw-shell contact of the base receptacle, and wherein the fuse plug has axial extent approximating the axial extent of 75

the conventional fuse plug, and has a center contact-carrying body portion for carrying the center contact of the plug axially through the sleeve into direct engagement with the center contact of the base receptacle, whereby the fuse plug projects from the base receptacle no more than does the conventional fuse plug.

Yet another object is to provide a tamper-resisting fuse plug having a standard screw-shell contact for screwing directly into the screw-shell contact of a standard cut-out base receptacle, and having an insulating body portion projecting axially within and beyond said screw-shell contact of the fuse plug and constituting one wall of a substantial annular chamber interiorly of the screw-shell contact of the fuse plug.

A further object is to provide a tamper-resisting fuse plug having means thereon for coaction with a tamper-resisting insulating sleeve which is mountable within a standard cut-out base receptacle, said fuse plug having standard screw-shell and center contacts directly engageable respectively with the conventional screw-shell and center contacts of the base receptacle both 25 when the tamper-resisting sleeve is in the base receptacle and when the sleeve is absent from the receptacle.

Another object is to provide a fuse plug cut-out assembly comprising a fuse plug, a cut-out base receptacle and a tamper-resisting sleeve, wherein the tamper-resisting sleeve and cut-out base may be integrally molded of insulation material, or the tamper-resisting sleeve may be separately formed for embodiment in the cut-out base 30 as an insert, said base receptacle in either case having a screw-shell contact for surrounding the tamper-resisting sleeve, in spaced relation thereto, and for directly receiving a screw-shell contact on the fuse plug, a body portion of the 35 fuse plug having dimensions for fitting within the tamper-resisting sleeve, and carrying a center contact for direct engagement with the center contact of the cut-out base receptacle.

An additional object is to provide a fuse plug cut-out assembly comprising a fuse plug, a cut-out base receptacle and a tamper-resisting sleeve, wherein the tamper-resisting sleeve is within the base receptacle and has a substantial outwardly projecting portion which is exteriorly threaded 45 and which has outside diameter only slightly less than the inside diameter of the screw-shell contact of the base receptacle, and wherein the fuse plug has a bare screw-shell contact for screwing into the receptacle with the screw-shell contact of the receptacle engaging it exteriorly and with said threaded portion of the sleeve engaging it 50 interiorly.

Another object is to provide a tamper-resisting generally tubular insulating member exteriorly threaded at two differing outside diameters thereof so that one of said threaded diameters is adapted to screw into the screw-shell contact of a fuse plug base receptacle and the other of said threaded diameters is adapted to screw into the screw-shell contact of a fuse plug when said screw-shell contact of a fuse plug is screwed into said screw-shell contact of the base receptacle.

It is, moreover, my purpose and object generally to improve the structure and adaptability of tamper-resisting fuse plugs and assemblies and more especially such fuse plugs and assemblies which may be designed also to resist over-fusing.

In the accompanying drawings:

Fig. 1 is a cross-sectional view of a fuse plug

mounted in a standard cut-out base receptacle and including inserted means within the receptacle coacting with the fuse plug to resist fuse-tampering;

Fig. 2 is a view, similar to Fig. 1, but showing the fuse plug operatively mounted in the base receptacle without the said inserted coacting means of Fig. 1;

Fig. 3 is an end elevation of the assembly of Fig. 1, in cross-section on line 3-3;

Figs. 4 and 5 are similar elevational views of two fuse plugs embodying features of my invention and having center contact-carrying body parts whose exterior diameters are appreciably different so that they are not interchangeable in any particular tamper-resisting insulating sleeve element;

Figs. 6 and 7 are similar elevational views of two tamper-resisting insulating sleeve elements having interior diameters for nicely accommodating each a particular one of the fuse plugs of Figs. 4 and 5, the sleeve element having the smaller interior diameter being adapted to reject the fuse plug having the larger exterior diameter;

Fig. 8 is a bottom plan view of my improved fuse plug showing serrations at the end of its center contact-carrying body part;

Fig. 9 is an elevation of the inner end portion of the plug of Fig. 8;

Fig. 10 is an elevation showing how my tamper-resisting sleeve element may be serrated at its outer end, to increase its breaking and cutting effect, in coaction with a fuse plug; and

Fig. 11 is a cross-sectional view through a cut-out base receptacle having my tamper-resisting sleeve formed as an integral part of the insulating body of the cut-out base.

Referring to the drawings, the cut-out base indicated generally at 10 may be of any suitable design and construction but preferably will be a standard Edison base, as shown, having the screw-shell contact 12 electrically connected to the terminal element 14 to which one line conductor may be connected by means of the binding screws 16. The usual center contact of the base is indicated at 18 electrically connected to terminal element 20 which is adapted for connection to the other line conductor by the binding screw 22.

My improved fuse plug, of tamper-resisting type, is indicated generally at 24, and it is a feature that the plug has a screw-shell contact 26 for screwing directly into the screw-shell contact 12 of the base receptacle, and has a center contact 28 for directly engaging the center contact 18 of the base receptacle. It should be noted that the screw-shell contact 26 and the center contact 28 have the same relation to each other as the screw-shell and center contacts of the conventional fuse plug, and that the axial overall extent of my improved plug may be the same as that of the conventional fuse plug. Fig. 2 illustrates the mounting of the fuse plug in the base receptacle without any adapter or other means additionally inserted in the receptacle. Hence, it will be readily seen that my improved fuse plug may be operatively mounted in any of the two hundred million presently installed standard Edison base receptacles substantially in the precise manner that regular fuses for years have been mounted, and with no greater axial projection from the receptacle than the conventional fuse plug. Also, my improved plug, as mounted in Fig. 2, provides the same degree of

70 circuit protection that has been given by a conventional fuse plug of the same rating.

In order to meet the requirements of the National Electrical Code, shortly to become mandatory for new fuse plug installations, my improved fuse plug 24 has an insulating body part 30 which extends axially within and beyond the screw-shell contact 26, and this body part 30 has exterior diameter substantially less than the interior diameter of the screw-shell contact 26, so that an annular chamber 32 of considerable depth intervenes between the body part 30 and the screw-shell contact 26 of the fuse plug. The center contact 28 of the fuse plug is mounted at the end of the insulating body part 30 and, as previously pointed out, is in substantially the same relation to screw-shell contact 26 as exists between the screw-shell and center contacts of the ordinary conventional fuse plug.

According to the invention, the insulating body part 30 of the fuse plug is adapted for coaction with a tamper-resisting insulating sleeve element 34 which preliminarily may be secured within the screw-shell contact 12 of the base receptacle whenever it is desired that any particular fuse plug assembly shall be resistive to fuse-tampering and over-fusing to a degree meeting the mandatory requirements of the Code for new installations. Fig. 1 illustrates my improved fuse

30 plug mounted in the standard cut-out base receptacle, with my tamper-resisting insulating sleeve element 34 in position within the base receptacle and projecting into the annular chamber 32 of the fuse plug in closely surrounding relation to the insulating body part 30 of the plug.

35 By comparison of Figs. 1 and 2, it will be seen that my improved fuse plug seats in the base receptacle in precisely the same manner both with and without the tamper-resisting sleeve 34 in place, and its axial projection from the receptacle is the same in each case. Both with and without the tamper-resisting sleeve 34, the center contact of the plug directly engages the center contact of the receptacle. However, with the sleeve in place, as in Fig. 1, its substantial annular extent within the screw-shell contact 26, and its closely surrounding relation to the insulating body part 30 of the plug make it extremely difficult to bridge or otherwise by-pass the fusible element of the plug either by make-shift means 40 inserted in the base receptacle or by displaced portions of either of the inter-engaged screw-shell contacts.

45 Furthermore, both my improved fuse plug 24 and my tamper-resisting insulating sleeve element 34 may be readily and economically produced according to conventional manufacturing procedures. The fuse plug body may be integrally formed in one piece of any suitable insulating material such as porcelain, glass, plastic, or a composition material. However, it is not necessarily made in one piece nor of one material throughout, but may, if desired, be partly of one material and partly of another material. As herein shown, the insulating body is an integral one piece structure having the head part 36, including the annular flange 38, with the previously mentioned body part 30 of smaller diameter projecting axially from the head.

50 The body is interiorly chambered to provide a relatively deep well 40 which is open through the head end of the body and covered by the customary disc of mica 42, or the like, held in place by the ring element 43 which conveniently 55 may be crimped over the flange 38 which may be

7
serrated at the region of crimping to lock the ring element against rotation on the plug body. The body part 30 may be variously shaped exteriorly but preferably has the generally cylindrical smooth surfaced exterior as shown for nicely fitting within the complementary axial hole through the insulating sleeve element 34.

The center contact 28 of the plug extends through the bottom wall of well 40 at the end of body part 30, and a usual deposit of relatively high temperature melting solder 44 or the like electrically connects the center contact 28 to the fusible element 46 whose one end is embedded in the solder 44 and whose other end extends into one of a pair of recesses 48 interiorly of the head part 36 and on opposite sides of well 40, where this end of element 46 is suitably anchored by means of a deposit of relatively high melting temperature solder 50, or the like. The screw-shell contact 26 of the plug conveniently and effectively may be mounted on the plug body by means of an annular inturned flange 52, at one end of the screw-shell contact, which seats on the shoulder 54 at the juncture of the head part 36 and the body part 30 of the insulating plug body, the flange 52 having oppositely arranged tongues 56 for extending each through an opening 58 into a different one of the interior recesses 48, where one becomes both anchored and electrically connected to the fusible element 46 by the said solder 50 and the other is anchored in the other recess 48 by a similar deposit of solder 60.

My tamper-resisting insulating element may be variously shaped so long as it provides a needed axial passage for projection of a plug center contact into direct engagement with a receptacle center contact. Figs. 1, 5, 7 and 10 show a preferred form of tamper-resisting element 34 which is generally tubular on toroidal in shape. It is adapted for securement as an insulating sleeve within the screw-shell contact 12 of the cut-out base with the inner end of the sleeve surrounding the center contact 18 of the cut-out base and with the main body of the sleeve projecting outwardly within the screw-shell contact 12.

It is a feature that the inner end portion of sleeve element 34 has outside diameter slightly greater than that of the outer end portion of the sleeve, and that both the larger and the smaller diameter portions are exteriorly threaded as at 62 and 64. The larger diameter portion 62 is adapted to screw into the screw-shell contact 12 of the cut-out base while the smaller diameter portion 64 is spaced inward of screw-shell contact 12 only enough to provide a narrow space for receiving the screw-shell contact 26 of the fuse plug 24, with the screw-shell contact 12 threadedly engaging the screw-shell contact 26 exteriorly and with the threads of the smaller diameter portion 64 of sleeve 34 in close proximity to the threaded walls of the screw-shell contact 26 interiorly. It will be obvious that there is practically no possibility of effecting a bridging of the center contact and the screw-shell contact of the base receptacle without the bridging means preventing screwing in of the fuse plug, or if the fuse plug is screwed into the receptacle, any bridging device necessarily will be severed and rendered inoperative as a bridge. Any suitable means at the periphery of the larger diameter threaded region 62 may be provided for locking the sleeve against removal after it has been initially screwed to an operative position

5
within the screw-shell contact 12. As shown, this locking means is a piece of wire 66 anchored at one end in a peripheral recess 68 and projecting resiliently outward slightly beyond the periphery, with the outer end sharpened and in position lagging behind the anchored end when the sleeve is being screwed into the screw-shell contact 12. Hence, the free sharp end of wire 66 rides freely on the inner surface of 10 the screw-shell contact 12 when the sleeve element 34 is being screwed into the receptacle but resists unscrewing by digging into the wall of screw-shell contact 12 when attempt is made to turn the sleeve in direction to remove it from 15 the receptacle. Or the wire 66 may engage in a cut-out 70 in the shell contact 12 when the sleeve is seated so that any attempt to unscrew the sleeve is effectively resisted by the wire 66 engaging a wall of the cut-out 70.

20 Each insulating sleeve element 34 has an axial hole 72 therethrough of size and shape to nicely accommodate the body part 30 of the fuse plug, while the main extent of the sleeve element enters 25 the annular chamber 32 of the fuse plug as a barrier for isolating from each other the center and screw-shell contacts of the assembly.

25 It will be obvious from an examination of Fig. 1 that insertion of a coin or a wad of tin-foil within the sleeve element 34 cannot complete a circuit between the center and shell contacts of 30 the assembly, assuming that the fusible element 46 of the plug has been blown. On the other hand, if a wire or other conducting element is 35 inserted into contact with both the center and shell contacts, the body part 30 of the plug, entering the sleeve element 34 with close clearance, and the screw-shell contact 26 of the plug entering between the sleeve element and the screw-shell contact of the base, will break or shear any 40 such element having a size capable of bridging the assembly. In other words, the coaction of 45 my improved fuse plug and my tamper-resisting insulating sleeve element 34 in a standard Edison base fuse receptacle provides a degree of resistance to fuse-tampering meeting all of the Code requirements in this respect.

50 Over-fusing may be effectively resisted with my improved fuse plug by slight variation of the body parts 30 of plugs having different rated capacities, and by a corresponding variation in the diameters of the axial holes in my tamper-resisting sleeve elements 34. For example, the body part 30 of fuse plugs having 0-15 ampere rating may have exterior diameter of $\frac{1}{4}$ of an 55 inch, while the body part 30 of fuse plugs of 16-30 ampere rating may have exterior diameter of $\frac{3}{8}$ of an inch. The axial holes in sleeve elements 34 similarly may be of two slightly different diameters so that the sleeve element 34 for a 60 0-15 ampere fuse plug will reject a fuse plug of 16-30 ampere rating. Of course, more than two variations may be provided, if desired. Figs. 4 and 6 represent fuse plugs of different ratings with the difference in the exterior diameter of 65 their body parts 30 exaggerated to make the difference visually apparent. Figs. 5 and 7 illustrate insulating sleeve elements 34 having axial holes respectively of size to nicely receive the body 30 of different plugs.

70 Obviously the Fig. 7 sleeve element will reject the Fig. 4 fuse plug.

75 From the foregoing, it will be obvious that I have provided a fuse plug of the tamper-resisting variety which is operatively mountable in standard cut-out base receptacles without any

adapter or other auxiliary insert in the receptacle. Yet my improved fuse plug is readily combinable with a tamper-resisting insulating sleeve element, which may be inserted in the standard cut-out base receptacle, to provide all of the protection against fuse-tampering and over-fusing which shortly will become mandatory under provisions of the National Electrical Code. My invention has the additional important advantage of making it possible and practicable for plug fuse manufacturers to produce only fuse plugs of the tamper-resisting variety without any need for continued manufacture of prior conventional fuse plugs to meet the replacement demands of present installations. My improved fuse plug can effectively serve, without need for any adapter, all of the replacement requirements of present installations, and can effectively meet the Code requirements for new installations by the mere inclusion of an inexpensive tamper-resisting sleeve element which in no way affects the operative electrical connections through a fuse plug assembly.

While I have shown a fuse plug having the mica disc 42 for visibility of the fusible element 46, a conventional transparent fuse plug head of glass or the like obviously may be employed, as is well known in the art. Also, I desire it to be understood that the axial hole 12 in the insulating sleeve elements 34, and the exterior surface of the plug body part 30, may be variously cooperatively shaped so long as the center contact of the fuse plug is adapted to be projected entirely through the sleeve element into direct engagement with the center contact of the base receptacle.

If desired, the end of the body part 30 of the plug and/or the entrance end of the sleeve elements 34 may be serrated or otherwise shaped to increase cutting or breaking coaction between the plug and sleeve as the plug enters the sleeve. Figs. 8 and 9 suggest such serrations or teeth at 74 on the end of the body part 30 of a fuse plug, and Fig. 10 suggests similar serrations or teeth 76 on the outer end of a tamper-resisting sleeve element 34.

While an insert type of tamper-resisting sleeve is desirable for use in the standard cut-out base receptacle presently installed, it may be desirable in future cut-out base receptacles to build the tamper-resisting sleeve in the base receptacle at the time of manufacture of the base receptacle. Fig. 11 illustrates a molded cut-out base receptacle structure whose main body 78 may be of Bakelite or any other suitable moldable insulating material, with the terminal elements 80, 82 embedded in the molded material. The screw-shell contact 84 is electrically connected to terminal element 80, and the center contact 86 is electrically connected to the terminal element 82. My preferred form of tamper-resisting sleeve 88, in this case, is molded as an integral part of the insulating body 78, with extent and arrangement within screw-shell contact 84 generally the same as in the previously described insert-type of Figs. 1, 5 and 7.

I claim as my invention:

1. A device for adapting a socket having a female screw-shell contact and a center contact and originally designed to receive a particular type of fuse plugs, for reception of only specially designed fuse plugs, said device comprising a generally tubular insulating element exteriorly threaded from end to end and having continuity of its threads from end to end, the threads at one

end portion having diameter for screwing into said socket screw-shell contact and the threads at the other end portion having smaller diameter for screwing into a fuse plug screw-shell contact which itself may be screwed into said socket screw-shell contact.

2. In a tamper-resisting fuse plug and socket assembly, a fuse plug screw-shell contact and a socket screw-shell contact adapted for screw-thread engagement, one within the other, and an exteriorly threaded insulating member having its threads at one region adapted to threadedly engage the outer one of said screw-shell contacts and having its threads at another region adapted to threadedly engage the inner one of said screw-shell contacts with said inner screw-shell contact intervening between the outer screw-shell contact and said insulating member at the latter said region.

3. In a tamper-resisting fuse plug and socket assembly, a fuse plug having a plug screw-shell contact and an insulating body part extending axially in spaced relation to said plug screw-shell contact, a plug center contact at the projected end of said insulating body part, a socket having a socket center contact and having a socket screw-shell contact adapted to threadedly engage said plug screw-shell contact thereby to directly engage said plug center contact with said socket center contact, and an insulating sleeve member disposed within said socket with one end portion surrounding said socket center contact and exteriorly threaded for threadedly engaging said socket screw-shell contact, the outer end portion of said sleeve member having smaller diameter and being exteriorly threaded for threadedly engaging said plug screw-shell contact.

4. In a plug fuse and socket assembly, a fuse plug having an insulating body part carrying a plug center contact at its end and having a plug screw-shell contact in surrounding spaced relation to said insulating body part whereby a substantial annular chamber is formed within the plug screw-shell contact, a socket having a socket center contact and having a socket screw-shell contact within which said plug screw-shell contact may be screwed to directly engage the two said center contacts, an insulating sleeve having an inner end portion surrounding said socket center contact and having an outer end portion for entering said annular chamber of the plug, said inner end portion of the sleeve being exteriorly threaded for screwing into said socket screw-shell contact and said outer end portion of the sleeve being exteriorly threaded for threadedly engaging said plug screw-shell contact when the latter is screwed into said socket screw-shell contact.

5. In a fuse plug base receptacle having a screw-shell contact, a tamper-resisting means within said screw-shell contact comprising a body of insulating material having a substantial portion with outside diameter only slightly less than the interior diameter of said screw-shell contact and having its exterior threaded, whereby said substantial portion of the insulating body is adapted to threadedly engage the inside while said screw-shell contact of the receptacle threadedly engages the outside of the threads of a screw-shell contact of a fuse plug when such a plug is screwed into the base receptacle.

6. A fuse plug assembly comprising a base having center and screw-shell contacts, a tamper-resisting insulating sleeve element having an ex-

teriorly threaded inner end portion for screwing into said screw-shell contact of the base, and having a portion of less exterior diameter exteriorly threaded and projecting a substantial distance in axial direction outward from said threaded inner end portion to provide an annular space between said screw-shell contact and said threaded outward projecting portion of the sleeve element, said sleeve element having an axial passage opening through its opposite ends and the walls of said passage, at the inner end of the sleeve element, being adapted to surround said center contact of the base when the sleeve element is screwed into said screw-shell contact of the base, and a fuse plug having a screw-shell contact for screwing into said screw-shell contact of the base and for simultaneously screwing on said exteriorly threaded outward projecting portion of the sleeve element, said fuse plug having a hollow center-contact-carrying portion of insulating material projecting axially within and beyond the screw-shell contact of the plug, in spaced relation thereto, and said hollow center-contact-carrying portion of the plug being adapted to pass through the axial passage of the sleeve element, and there being a center contact exposed only at the projected end of the center-contact-carrying portion of the plug for directly engaging the center contact of the base when it is projected through said axial passage in the sleeve 30 element.

7. In a fuse plug assembly having a fuse plug mounted in a base receptacle with a screw-shell contact of the plug screwed into a screw-shell contact of the base receptacle and with a center contact of the plug directly engaged with a center contact of the base receptacle, tamper-resisting means in the base receptacle comprising an insulating sleeve element having an axial passage opening through its opposite ends and having insulating walls of the passage surrounding the said engaged center contacts of the base receptacle and plug, said insulating sleeve element

having one portion exteriorly threaded and screwed into the screw-shell contact of the plug, and having another portion exteriorly threaded and screwed into the screw-shell contact of the base receptacle.

8. An insulating tamper-resisting insert for a fuse plug base receptacle, comprising a sleeve element of insulating material having an axial passage opening through its opposite ends, exterior 10 screw threads extending continuously from end to end of the sleeve element, said screw threads at one end portion of the sleeve element having diameter for screwing into a screw-shell contact of the base receptacle and said screw threads at the other end portion of the sleeve element having smaller diameter for screwing into a screw-shell contact of a fuse plug when said screw-shell contact of the fuse plug is screwed into said screw-shell contact of the base receptacle.
